UNITED STATES PATENT OFFICE.

JOSÉ MA. OLLER TINTORÉ, OF BARCELONA, SPAIN.

METAL-RING MOUTHPIECE WITH REVOLVING LIP FOR TINS, CANS, AND OTHER RECEP'TACLES.

Application filed December 3, 1924, Serial No. 753,712, and in Spain December 3, 1923.

This invention relates to a mouthpiece for cans and the like.

Tins and cans for holding oil and other liquids generally have a mouthpiece with a fixed or revolvable lip soldered thereon. With a revolving lip the turning movement is not limited and it is difficult to place it in any predetermined position without this position varying during the process of emptying the can.

The mouthpiece of this invention has a revolvable lip disposed in such a way that the revolving movement thereof is limited, one of the extreme positions corresponding to that for emptying, and the other placing the lip within the can borders for preventing spilling.

In this mouthpiece, a lip is screwed onto a metal ring, so that the latter forms an outjutting flange against which the lip strikes on being unscrewed. On soldering the mouthpiece to the can, its position is so adjusted that the lip, while touching the flange of the mouthpiece, occupies the emptying position. On turning the lip it is brought to lie within the plan projection of the can.

In the accompanying drawings;

Fig. 1 is a vertical section of the invention.

Fig. 2 is a top plan view of the same.

Fig. 3 is a side elevation of a stopper with which the mouthpiece is closed.

A pouring lip 7 has an annular body 5 provided with a screw thread to thread onto a mouthpiece 2, soldered, at its flange 4, to an opening in the can top 1. The upper edge 3, of the mouthpiece 2, is spread outwards to form a stop to limit the rotation of the lip 7 thereon, so that the part 5, when the lip 7 reaches a convenient position for pouring, binds on the mouthpiece to limit its movement.

During the process of manufacturing the can, in order to apply the mouthpiece 2, the lip 7 is previously screwed upon it, until it

strikes against the edge 3, when the mouthpiece is soldered to the can so that the lip is in a position convenient for pouring, that is, directed to project beyond one of the sides of the can, or, better still, beyond one of the corners, as shown in Figure 2. For packing the cans, each lip is turned in the direction of arrow 17, until it assumes the dotted line position 70. For emptying a can, the lip is turned in the opposite direction to the fuel line position of Figs. 1 and 2, when its movement is stopped on the thread 2.

The flange 4 of member 2 serves as a bottom for a cap 8 for preventing liquid from flowing out of the can.

The mouthpiece 3 can receive a stopper 9 (Figure 3) the lower end 11 of which stopper is provided with a washer 10 held thereon by means of a cap 12.

As a result, when the can is to be emptied, the lip occupies a fixed position, and juts out over the edge or corner of the can and when the operation of emptying is finished, the lip can be placed in a position to facilitate transport of the can.

What I now claim, is:

1. An improvement in cans, comprising a sheet metal mouthpiece stamped to form an exterior-interior thread, a threaded plug and a threaded pouring lip member engaging respectively the inside and outside of said thread in a common zone of said mouthpiece.

2. An improvement in cans as claimed in claim 1, the mouthpiece being flared at its outer end to form a stop for said pouring lip member against which the latter abuts at a point in its rotation, at which the pouring lip extends beyond the edge of the can.

In testimony whereof I have signed my name to this specification.

JOSÉ MA. OLLER TINTORÉ.
